Primary Examiner — Karen S Acker*Assistant Examiner* — Wendy L Arminio(74) Attorney, Agent, or Firm — Edell, Shapiro & Finnian, LLC(57) CLAIM

The ornamental design for a fabric including surface ornamentation, as shown and described.

DESCRIPTION

FIG. 1 is a view in perspective of fabric including surface ornamentation showing my new design; and, FIG. 2 is a top plan view thereof.

The broken lines in the drawings depict the boundaries of the claimed design and form no part thereof. The opposite side of the fabric including surface ornamentation is flat and unornamented; accordingly, a figure showing the opposite side has been omitted.
